ABSTRACT OF THE DISCLOSURE

An improved process for the production of bright stock of improved pour point and hazing characteristics which process comprises blending a residual lubricating oil stock with slack wax and then subjecting the blend to solvent dewaxing.

This application is a continuation-in-part of our co-pending application Ser. No. 553,727, filed May 31, 1966 now abandoned.

Our invention relates to an improved process for producing bright stocks from certain residual derived stocks.

It has previously been suggested in the art to prepare lubricating oils, including bright stocks, by subjecting crude lubricating oil stocks to a variety of treatments including deasphalting, solvent extraction, comparatively severe hydrogen treatment, sometimes called hydrotreating, solvent dewaxing, acid treatment, clay contacting and more recently, mild hydrogen treatment, sometimes called hydrofinishing. This last mentioned mild hydrofinishing operation in many instances is employed in lieu of acid treatment and clay contacting and is employed mainly in the treatment of lubricating oil base stocks, as distinguished from crude lubricating oils, in order to remove odor and color forming materials which are considered to be objectionable in the final lubricating oil product. All of the above-mentioned operations contribute to the production of the final finished lubricating oil from the crude lubricating oil stock by removing undesirable constituents and/or hydrocarbon types from either the crude lubricating oil stock or the intermediate lubricating oil base stock. Generally, the prior art does not suggest any preferred order in which these various operations are to be conducted other than that dictated by economic or engineering expediencies such as, for example, employing previously a treating technique which is effective to remove materials deleterious to subsequent treatment steps or which reduces the quantity of material to be treated in a subsequent step, the operation of which is more expensive.

One of the required characteristics or properties of a finished lubricating oil is that it be clear or bright and free from any cloud or haze even after storage at a low temperature for a period of time. In many instances this desirable characteristic or property of a lubricating oil can be obtained when employing any combination of one or more of the above-mentioned treating techniques. A typical example of the prior art operation includes solvent dewaxing an intermediate lubricating oil base stock followed by acid and clay contacting of the dewaxed base stock. In more modern refinery operations this scheme would require solvent dewaxing of a lubricating oil base stock followed by hydrofinishing of the dewaxed material to yield the finished lubricating oil. While this sequence of operations may in some instances be entirely satisfactory to yield a lubricating oil having good hazing properties, it has been found that in many instances it is quite unsatisfactory.

2

Another of the required characteristics or properties of a finished lubricating oil is that it have a low pour point. The desired level of the pour point of a finished lubricating oil varies, depending upon the type of finished lubricating oil desired as a product and its intended employment. 5 Usually, however, a pour point of +10° F. or lower is required. In some instances the desired pour point may even be as low as -40° F. or even lower. In most instances, however, a finished lubricating oil having a 10 pour point of about -5° F. to about +5° F. is satisfactory. The art has recognized for many years that the pour point of a lubricating oil is generally related to the quantity of wax present in the material and a variety of dewaxing techniques have been suggested to lower the wax 15 content of lubricating oils and concomitantly lower the pour point thereof. Presently, the technique employed widely in the art is a solvent dewaxing operation. Even though present day solvent dewaxing techniques are generally considered to be somewhat of an improvement over 20 techniques previously employed in the art, the solvent dewaxing treatments are still beset by the traditional problem in the dewaxing field, i.e. the wax cannot be removed from the lubricating oil without cooling the material being treated to an extremely low temperature, 25 usually lower than the desired pour point of the finished product. Thus, the limiting factor in most solvent dewaxing operations is the refrigeration capacity of the unit and any technique which would permit obtaining the 30 desired pour point of the treated material but permit employment of a dewaxing temperature even a few degrees above what might otherwise be required, results in a substantial improvement and enhancement of the process from an economic viewpoint.

In many instances this desirable characteristic of a low 35 pour point in a lubricating oil can be obtained when employing a solvent dewaxing treatment in combination with any one or more of the treating techniques mentioned previously. A typical example of the prior art operation includes solvent dewaxing an intermediate lubricating oil 40 base stock followed by acid and clay contacting of the dewaxed base stock. In more modern refinery operations this scheme would require solvent dewaxing of a lubricating oil base stock followed by hydrofinishing of the dewaxed material to yield the finished lubricating oil. 45 While this sequence of operations may in some instances be entirely satisfactory to yield a lubricating oil having the desired pour point in an economical manner, it has been found that in many instances this sequence is not advantageous.

50 We have discovered that, when treating lubricating oil base stock derived from a residual material in order to produce bright stocks, the more conventional techniques of lubricating oil treatment are not satisfactory to produce a finished bright stock which is free of haze. Thus, for 55 example, when employing the conventional technique of fractionating the entire crude lubricating oil into the various boiling range fractions required to produce light, medium and heavy distillate lubricating oils as well as bright stocks and then subjecting these individual fractions to 60 solvent extraction such as, for example, furfural extraction, under the particular different operating conditions which are optimum for each of the fractions and then dewaxing and hydrofinishing the fractions, the bright stock product obtained is usually quite hazy. We have found, 65 however, that a haze-free bright stock product can be obtained in accordance with our invention if the lubricating oil base stock derived from a residual material, which is the source of the bright stock, is blended with paraffinic wax of the type present in distillate crude lubricating oils and distillate lubricating oil base stocks and then the blend 70 is subjected to solvent dewaxing. The production of the

finished bright stock would, of course, also require a hydrofinishing treatment.

The particular materials which are to be treated in accordance with the process of our invention and which are the typical materials from which finished bright stocks are usually obtained can be described as having been derived from a residual material. Normally, a residual material or residuum can be defined as the higher boiling, difficultly vaporizable components of petroleum hydrocarbons. These difficultly vaporizable materials are usually of such a high boiling point that there is a tendency to effect some cracking prior to or along with distillation at atmospheric pressure. Generally, these materials will be found to boil above about 900° or 925° F. and include those materials which can only be distilled, without cracking, under a vacuum. It is lubricating oil base stocks derived from such residual materials that are contemplated for employment in our process. Generally, by the term lubricating oil base stock is meant a fraction or group of fractions usually produced at an intermediate point in the production of a lubricating oil which lacks but the final finishing operations, such as, for example, dewaxing, hydrofinishing, acid treatment or clay contacting, before being classed as a finished lubricating oil. Normally, such lubricating oil base stocks can be obtained from crude lubricating oil stocks, i.e. untreated materials boiling in the general lubricating oil range of 650° F. +, by atmospheric and vacuum distillation followed by various treatments, including solvent extraction, treatment in a Duo-Sol process, comparatively severe hydrogen treatment, i.e. hydrotreatment, etc. or any combination of these treatments depending mainly on the type of crude lubricating oil being considered and the type of finished lubricating oil desired as product.

The particular lubricating oil base stock contemplated for treatment in accordance with our invention is, as mentioned above, a residual derived lubricating oil base stock and such material will usually have been subjected to a deasphalting treatment such as propane deasphalting. As distinguished from this particular lubricating oil base stock, which is the source of finished bright stock, the remaining lower boiling lubricating oil base stocks can be termed distillate lubricating oil base stocks and the portion of the crude lubricating oil from which they are obtained can similarly be termed a distillate crude lubricating oil. At times, however, there may be a certain overlap in the boiling ranges of what are termed distillates as distinguished from the residual derived lubricating oils or lubricating oil base stocks. Thus, while the residual derived materials will generally have an initial boiling point of 900° or 925° F. or above they will usually be found to have a 5 percent boiling point closer to 950° F. and a 10 percent boiling point above 950° F. On the other hand, however, while certain of the heavier distillate lubricating oil base stocks may have 90 percent boiling points or end boiling points as high as about 1000° F. they will usually be found to have 10 percent boiling points substantially below 900° F. but with initial boiling points and at least 5 percent boiling points of 650° F. or higher.

The residual derived lubricating oil base stocks treated in accordance with our invention can also have a comparatively high sulfur content, such as, for example, about 0.75 percent by weight or greater. In many instances it will be found that these stocks contain at least about 1.0 percent by weight sulfur.

The paraffinic wax which is blended with the residual derived lubricating oil base stock in accordance with our invention is of the type normally present in distillate crude lubricating oils or distillate lubricating oil base stocks and thus comprises waxes boiling above about 650° F. and preferably above about 700° F. These waxes are well-known in the field of lubricating oil production and, for example, when this paraffinic wax has been removed from a distillate lubricating oil base stock by means of solvent dewaxing the wax recovered is generally termed a slack

wax. It is within the scope of our invention to add the paraffinic wax to the residual derived lubricating oil base stock either in the form of the wax itself, such as, for example, a deoiled slack wax or a slack wax, or to introduce such paraffinic wax into the blend simply by adding a quantity of a distillate lubricating oil base stock containing such paraffinic wax to the residual derived lubricating oil base stock. We have found that it is advantageous to select, as the source of paraffinic wax, a distillate lubricating oil base stock boiling in a range substantially below that in which the residual derived lubricating oil base stock boils. The reason for this is that it is theorized that when employing a distillate lubricating oil base stock of a higher boiling range, the wax contained therein or obtained therefrom is composed of a greater proportion of microcrystalline wax whereas the extremely light lubricating oil base stocks contain substantially no microcrystalline wax. Thus, for example, we prefer to employ as the source of the paraffinic wax a distillate lubricating oil base stock having a 90 percent boiling point of about 100° F. lower than the 5 percent boiling point of the residual derived lubricating oil base stock and preferably about 100° F. lower than the initial boiling point of the residual derived stock.

When practicing our invention and employing the technique of adding the slack wax alone to the residual derived lubricating oil base stock, it is generally satisfactory to add to the base stock a quantity of slack wax equal to about 5 to about 50 percent by volume of the base stock. Preferably, however, the amount of the paraffinic wax added will be equal to about 10 to about 35 percent by volume of the residual derived base stock. When it is desired to blend paraffinic wax containing distillate lubricating oil base stocks with the residual derived lubricating oil base stock we have found that it is satisfactory to employ a quantity of distillate base stock equal to at least about 30 percent by volume of the residual derived stock. Generally, however, we prefer to employ at least about a 50-50 blend of distillate base stock and residual derived base stock.

In the solvent dewaxing treatment of our invention we have found that any of the well-known solvents employed in the art to effect dewaxing are quite satisfactory. Generally, we prefer to employ methylethylketone and toluene in about a 50-50 mixture as the solvent. The particular temperature employed in the solvent dewaxing treatment in accordance with our invention is usually about 5° F. or more above that required when not employing our processing sequence in order to provide a product having the desired pour point, usually about +10° F. or lower.

In the hydrofinishing operation of our process the operating conditions employed can include a temperature from about 400° to about 850° F. and preferably from about 600° to about 750° F., a pressure in the range from about 800 to about 3000 p.s.i.g. and preferably from about 1000 to about 2000 p.s.i.g., a liquid hourly space velocity in the range from about 0.1 to about 10.0 and preferably from about 1.0 to about 4.0 volumes of lubricating oil base stock per volume of catalyst per hour and a hydrogen circulation rate in the range from about 1000 to about 20,000 s.c.f./b. and preferably from about 2000 to about 7000 s.c.f./b. The catalyst employed in the hydrofinishing operation in accordance with our invention can be any of the hydrogenating catalysts well-known in the art, such as, for example, Group VI and Group VIII metals, their oxides and sulfides, or mixtures thereof, either alone or supported on a suitable carrier. Examples of catalysts which we have found to be advantageous for use in our invention are combinations of nickel, cobalt and molybdenum on an alumina support, such as, for example, a catalyst of the type described in U.S. Pat. 2,880,171, and a combination of nickel and tungsten on 70 alumina. Catalysts such as these can also contain a small

quantity of silica, such as, for example, less than about 5 percent by weight or even lower.

In order to illustrate our invention in greater detail, reference is made to the following examples.

EXAMPLE I

In this example a crude lubricating oil stock obtained from a reduced Kuwait crude having components boiling up to about 1100° F. was subjected to vacuum distillation so as to separate the crude lubricating oil into light, medium and heavy distillate fractions as well as a bottoms fraction. The inspections for these various fractions are shown in Table I below.

TABLE I

	Light distillate	Medium distillate	Heavy distillate	Bottoms
Inspections:				
Gravity, °API	25.2	20.6	17.7	6.5
Viscosity, SUS at—				
100° F	114.6	475	1,700	—
210° F	40.0	57.5	94.0	8,980
300° F				680
Sulfur, percent by weight	2.45	2.91	3.65	5.3
Carbon residue, grams, percent by wt	0.11	0.50	1.07	12.8
Distillation, ASTM D1160, ° F. at—				
5%	692	788	871	—
10%	702	804	887	—
30%	736	831	911	—
50%	756	852	934	—
70%	782	882	962	—
90%	823	932	1,012	—
95%	841	967	1,046	—

The bottoms fraction was then subjected to propane deasphalting at a pressure of 500 p.s.i.g., a temperature at the tower top of 150° F. and at the tower bottom of 120° F. The inlet temperature of the oil was 127° F. The ratio of propane to oil on a volume to volume basis employed in predilution was 0.5 and in the stripping was 7.5, yielding 31.8 percent by volume of deasphalting oil having an API gravity of 20.5, a viscous SUS at 210° F. of 196 and containing 2.76 percent by weight sulfur. The light and medium distillates were then blended together and subjected to furfural extraction while the heavy distillate and deasphalting bottoms fractions were each subjected to furfural extraction separately. The particular operating conditions employed in each of the three solvent extractions together with inspection data of the raffinates obtained is shown in Table II below.

TABLE II

	Light-medium distillate	Heavy distillate	Bottoms
Furfural extraction:			
Conditions:			
Solvent/oil, vol./vol	1.5	2.2	3.5
Tower top temp., ° F	200	220	270
Tower bottom temp., ° F	150	170	210
Charge temp., ° F	175	200	250
Raffinate yield, percent by vol	64.0	55.0	62.5
Inspections:			
Gravity, °API	29.5	26.9	25.4
Viscosity, SUS at—			
100° F	197.1	590	—
210° F	47.3	69.9	158.0
Viscosity index	111	102	—
Sulfur, percent by wt	1.19	1.53	1.57

The solvent extracted, paraffin wax containing light-medium and heavy distillate fractions were then blended with the bottoms fraction and subjected to solvent dewaxing employing a 55-45 blend of methyl ethyl ketone and toluene at a solvent to oil ratio, on a volume to volume basis, of 4.5 and at a temperature of -15° F. The amount of paraffin wax in the distillate fraction was equivalent to about 35 percent by volume of the bottoms fraction. This dewaxed blend was then subjected to hydrofinishing at a temperature, measured at bed outlet, of about 700° F., a pressure of 1650 p.s.i.g. and a liquid hourly space velocity of 3.0. The hydrofinished lubricating oil was then fractionated to obtain finished light, medium and heavy distillate lubricating oils and a finished bright stock.

Another bottoms fraction obtained from the same Kuwait crude mentioned above was subjected to propane deasphalting and furfural extraction under substantially the same conditions described above so as to provide a deasphalting, solvent extracted bottoms fraction substantially identical to that shown in Table II. This bottoms fraction was then separately subjected to dewaxing, i.e. in the absence of any light, medium or heavy distillate, after which it was subjected to hydrofinishing under the same conditions set forth previously. The following Table III shows comparative inspection data on the two finished bright stocks obtained in accordance with the two techniques described above, i.e. dewaxing the bright stock

10

alone and dewaxing the bright stock and distillate fractions together.

TABLE III

	Bright stock alone	Bright stock plus distillats
Dewaxing temperature, ° F	-15	-15
Finished bright stock:		
Viscosity, SUS/210° F	154.4	151.7
Pour point, ° F	0	-10
Haze test, appearance:		
48 hours at 40° F	(1)	(2)
At 46° F. in dar, days to visible haze	1	45

¹ Light haze.

² No haze.

From the data in Table III above it will readily be seen that when operating in accordance with the process of our invention wherein the paraffinic wax containing distillate fractions are blended with the residual derived bright stock source the finished bright stock obtained is haze-free while the finished bright stock product from the more conventional operation wherein the bright stock is dewaxed separately is subject to a hazing problem. It will also be noticed that while both bright stocks were dewaxed at the same temperature of -15° F. the finished bright stock obtained in accordance with our invention had a pour point of -10° F. as opposed to the pour point of 0° F. of the more conventionally obtained finished bright stock. Thus, in addition to eliminating the hazing problem in bright stocks the process of our invention also permits a significant saving in refrigeration capacity required in the dewaxing unit.

In attempting to obtain a finished bright stock by the more conventional technique of separately dewaxing, we have found that it has been necessary to employ a dewaxing temperature of -25° F. to provide a finished bright stock having a pour point of -10° F., thus substantiating the fact that the process of our invention consistently effects a savings in refrigeration capacity of about 10° F. in obtaining a finished bright stock.

70

EXAMPLE II

In this example a crude lubricating oil stock obtained from a reduced Kuwait crude having components boiling up to about 1100° F. and above was subjected to vacuum distillation so as to separate the crude lubricating oil into light, medium and heavy distillate fractions as well as

a bottoms fraction. The inspection data for this bottoms fraction were identical to those shown for the bottoms fraction in Table I of Example I. This bottoms fraction was then subjected to propane deasphalting under the same conditions set forth in Example I so as to provide a deasphalted oil having the same API gravity, viscosity and sulfur content as is also set forth in Example I. This deasphalted bottoms fraction was then subjected to furfural extraction, again employing the operating conditions employed for the bottoms fraction in Example I and set forth in Table II thereof. The results of this solvent extraction were substantially the same as those obtained in Example I providing a yield of 62 percent by volume of raffinate having an API gravity of 25.4, a viscosity SUS at 210° F. of 158 and a sulfur content of 1.31 percent by weight. This deasphalted, solvent extracted bottoms fraction was then separately subjected to solvent dewaxing employing a 55-45 blend of methyl-ethylketone and toluene at a solvent to oil ratio, on a volume to volume basis, of 5.4 and at a filtration temperature of -16° F. After having been dewaxed, the bottoms fraction was then hydrofinished at a temperature, measured at bed outlet, of about 675° F., a pressure of 1755 p.s.i.g. and a liquid hourly space velocity of 1.7. The effluent from the hydrofinishing operation was then passed to a stripper from whence was obtained a bottoms stream in a yield of about 96 percent by volume based on charge to the hydrofinisher and a small side stream in a yield of about 6 percent by volume based on the charge to the hydrofinisher. The finished bright stock of the bottoms stream had a viscosity index of 98 and a pour point of 0° F. while the finished side stream had a viscosity index of 95 and a pour point of +5° F. After 48 hours at 40° F. samples of the finished bright stock from the bottoms stream showed a light haze while samples from the side stream showed heavy floc.

In another operation in which the distillate fractions are also dewaxed separately from the deasphalted and solvent extracted bottoms fraction, a portion of the slack wax obtained from dewaxing the distillate fractions is blended with the bottoms fraction in an amount equivalent to about 15 percent by volume of the bottoms fraction prior to subjecting it to dewaxing. The blend of slack wax and bottoms fraction is then dewaxed under substantially the same conditions described above regrading the dewaxing of bottoms fractions, after which the dewaxed oil is subject to hydrofinishing, again under substantially the same conditions described previously in this example, to provide a finished bright stock. This particular finished bright stock shows no hazing tendencies after storage at 40° F. for a period of 48 hours.

EXAMPLE III

In this example a crude lubricating oil obtained from a comparatively low sulfur content Mid-Continent crude oil having components boiling up to about 1100° F. and above is subjected to vacuum distillation to provide light, medium and heavy distillate fractions as well as a bottoms fraction boiling generally above about 900° F. with a 10 percent point of about 1000° F. The bottoms fraction is solvent deasphalting and then each of the crude lubricating oil fractions, i.e. the light, medium and heavy distillate fractions and the deasphalted bottoms fraction, is separately subjected to solvent extraction with a solvent selective for aromatics. Each of the intermediate lubricating oil base stocks obtained as the raffinate from the solvent extraction of the distillate fractions is then separately subjected to solvent dewaxing whereby slack wax is removed and the dewaxed distillate fractions are separately hydrofinished to yield finished distillate lubricating oils. The intermediate bright stock lubricating oil base stock obtained by deasphalting and solvent extracting the bottoms fraction and containing about 0.4 percent by weight sulfur is divided into two portions. One of these portions is then subjected to solvent dewaxing and the

dewaxed material is then hydrofinished to produce a finished bright stock. The other portion of the lubricating oil base stock derived from the bottoms fraction is blended with a portion of deoiled slack wax obtained from the distillate fractions employing a quantity of deoiled slack wax equal to about 25 percent by volume of the lubricating oil base stock. This blend is then subjected to dewaxing followed by hydrofinishing of the dewaxed material to provide a second finished bright stock. After storage at 40° F. for a period of 48 hours the finished bright stock obtained from the first fraction, which was dewaxed in the absence of additional deoiled slack wax, was found to have a light haze whereas the finished bright stock obtained from the second fraction, which was dewaxed in the presence of additional deoiled slack wax, showed no haze.

EXAMPLE IV

In this example a light distillate lubricating oil stock boiling in the range from above about 650° F. to about 850° F. was subjected to a conventional dewaxing treatment. The dewaxed light distillate lubricating oil stock and the slack wax obtained from the dewaxing were then recovered and subjected to a boiling range determination. Inspection data for both the undewaxed and the dewaxed light distillate lubricating oil as well as the slack wax are set forth below in Table IV.

TABLE IV

		Unde-waxed distillate	Dewaxed distillate	Slack wax
30	Distillation, ASTM D1160 (° F.):			
	5%	709	693	693
	10%	714	701	702
	30%	735	721	712
35	50%	758	743	735
	70%	782	771	765
	90%	835	825	809
	95%	837	852	834

From the above data it will be seen that the slack wax obtained from a distillate lubricating oil stock is comprised of waxes of substantially the same boiling range as the lubricating oil from which obtained.

EXAMPLE V

In this example a residual derived lubricating oil base stock containing at least 0.75 percent by weight sulfur is first subjected to hydrofinishing after which the hydrofinished stock is blended with about 25 percent by volume based on the hydrofinished stock of a slack wax obtained from a distillate lubricating oil stock boiling above 650° F. The blend of hydrofinished stock and slack wax is then subjected to dewaxing to produce a finished lubricating oil having greatly enhanced hazing characteristics and capable of being stored at 10° F. for 48 hours without showing any tendencies to form floc.

55 We claim:

1. An improved process for producing a bright stock from a lubricating oil base stock derived from a residual material boiling above about 900° F. which process comprises blending the residual derived lubricating oil base stock with from about 5% to about 50% by volume of said base stock of a slack wax obtained by solvent dewaxing a material boiling above about 650° F. and selected from the group consisting of distillate crude lubricating oils and distillate lubricating oil base stocks and then subjecting the blend to solvent dewaxing.
2. The process of claim 1 wherein the slack wax is deoiled slack wax obtained by solvent dewaxing a distillate lubricating oil base stock to yield slack wax and then deoiling the slack wax.
3. The process of claim 1 which further includes subjecting the dewaxed blend to hydrofinishing.
4. The process of claim 3 which further includes fractionating the dewaxed and hydrofinished blend so as to separate the finished bright stock from lighter components.

5. The process of claim 1 wherein the residual derived lubricating oil base stock contains at least about 0.75 percent by weight sulfur.

6. The process of claim 1 wherein the residual derived lubricating oil base stock has a 10 percent boiling point above about 950° F.

7. The process of claim 2 wherein the distillate lubricating oils and distillate lubricating oil base stock boil in a range at least about 100° F. below the boiling range of the residual derived lubricating oil base stock.

8. An improved process for producing a bright stock from a lubricating oil base stock containing at least about 0.75% by weight sulfur and derived from a residual material boiling above about 900° F., which process comprises subjecting the residual derived lubricating oil base stock to hydrofinishing and thereafter blending the hydrofinished lubricating oil base stock with from about 5% to about 50% by volume of said hydrofinished base stock of a slack wax obtained by solvent dewaxing a material boiling above about 650° F. and selected from the group

10 consisting of distillate crude lubricating oils and distillate lubricating oil base stocks and then subjecting the blend to solvent dewaxing.
